UNITED STATES PATENT OFFICE.

JACOB KATZENBERG, OF NEW YORK, N. Y.

SUSPENDERS.

SPECIFICATION forming part of Letters Patent No. 441,491, dated November 25, 1890.

Application filed August 28, 1890. Serial No. 363,336. (No model.)

To all whom it may concern:

Be it known that I, JACOB KATZENBERG, of the city, county, and State of New York, have invented a new and useful Improvement in 5 Suspenders, of which the following is a full, clear, and exact description.

My invention relates to improvements in suspenders and shoulder-braces; and the object of my invention is to produce a pair of 10 suspenders that may be cheaply constructed and that will conform to the varying movements of the body of the wearer, thereby enabling them to serve admirably as supports for the trousers, and also causing them to be 15 very easy to the wearer.

To this end my invention consists in certain features of construction and combinations of parts, which will be hereinafter described and claimed.

20 Reference is to be had to the accompanying drawings, forming a part of this specification, in which similar letters of reference indicate corresponding parts in both the figures.

Figure 1 is a rear elevation of a pair of 25 suspenders embodying my invention, and Fig. 2 is a cross-section on the line 2 2 of Fig. 1.

The suspenders have the usual shoulder-straps A, which are provided at their front and rear ends with the usual tabs B, adapted 30 to be buttoned to the trousers, and the shoulder-straps are connected in the rear by the plates C, the plates being united by elastic lacings E, which extend through the eyelets e of the plates, and are fastened in any convenient manner. The outer edges of the plates 35 C are lapped upon the shoulder-straps A, and are held in place by the straps or covers D, which are laid over the outer edges of the plates and are firmly stitched to the shoulder- 40 straps, the stitches being passed through the plates C, so that the shoulder-straps, the plates, and the covers are all firmly bound together. It is desirable that the shoulder-straps be curved laterally toward each other, as shown 45 in Fig. 1, so that the ends thereof will diverge, as this form enables the straps to fit the body of the wearer, and the covers D are shaped to give the straps this peculiar form. The covers D correspond in width to the width of 50 the straps, and the inner edges of the covers are curved, as at d, the covers having rounded

ends d', or the ends may be pointed or scalloped, if desired. When the covers are attached to the shoulder-straps, the inner edges of the straps are stretched, so as to give them 55 the desired curvature, and the covers are attached while the straps are held in this position, and after the covers are stitched to the straps they serve to hold the straps in the curved position. By having the plates C interposed between the shoulder-straps A and the covers D the plates are held away from the body of the wearer, so that the eyelets therein will not become moistened by sweat and will not be likely to corrode. At the same 60 time the flexible connection between the plates permits of a free movement of the body and of the lacings.

I am aware that heretofore shoulder-straps have been united by a flexible connection, 70 and that shoulder-straps have been curved laterally, and I therefore do not claim these features, broadly, as my invention, but where the straps have been curved, as described, they have always been formed of two or more 75 pieces.

The plates C and covers D serve to strengthen the back of the wearer, and when the plates are used the eyelets therein may be small, and the lacings and eyelets will be held away 80 from the body, so that they will not be noticed in the least. The plates C being thin permit the use of a much smaller eyelet than is ordinarily used.

Having thus described my invention, I 85 claim as new and desire to secure by Letters Patent—

The suspenders comprising the laterally-curved shoulder-straps, each formed of a single piece, the back plates attached to the 90 backs of the straps at their converging points, said plates having their abutting edges perforated and connected by cross-lacings, and the binding strips or covers shaped to fit the curvature of the straps, said strips being attached to the backs of the straps and to the 95 back plates, substantially as described.

JACOB KATZENBERG.
